Primary Examiner—Susan Moon Lee*(74) Attorney, Agent, or Firm*—Stuart M. Goldstein(57) **CLAIM**

The ornamental design for a modular bird feeder, as shown and described.

DESCRIPTION

FIG. 1 is an isometric view of the modular bird feeder design of the present invention.

FIG. 2 is the front view of the modular bird feeder design of the present invention.

FIG. 3 is the rear view of the modular bird feeder design of the present invention.

FIG. 4 is an elevation view of the modular bird feeder design of the present invention.

FIG. 5 is the opposite elevation view of the modular bird feeder design of the present invention.

FIG. 6 is a top view of the modular bird feeder design of the present invention; and,

FIG. 7 is the bottom view of the modular bird feeder design of the present invention.

The broken lines in FIGS. 1-7 showing a lower support of the modular bird feeder design of the present invention are included for the purpose of illustrating use and environment and form no part of the claimed design.

1 Claim, 4 Drawing Sheets# US D623,805 S
